UNITED STATES PATENT OFFICE.

ALBERTUS O. SLENTZ, OF CANTON, OHIO, ASSIGNOR OF ONE-HALF TO THE CANTON FOUNDRY AND MACHINE COMPANY, OF CANTON, OHIO, A CORPORATION OF OHIO.

TURN-TABLE.

971,796.

Specification of Letters Patent.

Patented Oct. 4, 1910.

Application filed July 30, 1910. Serial No. 574,630.

To all whom it may concern:

Be it known that I, ALBERTUS O. SLENTZ, a citizen of the United States, residing at Canton, in the county of Stark and State of 5 Ohio, have invented a new and useful Turn-Table, of which the following is a specification.

My invention relates to turn tables of what may be termed the knock-down variety 10 wherein the various parts composing the device may be disconnected from each other and readily bundled or packed for shipment, the said parts being so constructed that they may be readily assembled and 15 placed in position ready for use with but little skill and labor.

Turn tables of this class are frequently used in automobile garages, but the practical use of such devices is not at all so limited, such tables being employed in a large 20 number of other instances where it is desired to provide a revolving platform capable of being arranged flush with the floor and capable of supporting a considerable 25 weight while being easily rotated.

The objects of my invention are to generally improve devices of the character mentioned; to construct a turn table possessing great strength and so arranged as to revolve 30 with the greater portion of the weight carried by said table supported on a bearing of relatively small circumference, provision being made for carrying any over-weight or unbalanced weight upon a second auxiliary 35 bearing of greater circumference.

Another object of my invention is to provide a turn table so constructed that it may from time to time be adjusted, as circumstances may require, to maintain the parts in 40 proper position with reference to each other, especially should they become strained or bent from any cause.

These and other objects apparent to those skilled in the art, I attain by the construction illustrated in the accompanying drawing, although my invention may be embodied in other forms, the construction illustrated being chosen by way of example.

Figure 1 is a top plan view of my turn 50 table showing parts removed and still other parts broken away. Fig. 2 is a perspective view of one of the trusses. Fig. 3 is a vertical sectional view of a truss taken on the line 3—3 of Fig. 2. Fig. 4 is a top plan view

of the turn table support. Fig. 5 is a top 55 plan view of the inner track. Fig. 6 is a sectional view showing a part of the inner track. Fig. 7 shows the ends of two segments and a connecting block, also a fragmentary end of one of the trusses removed 60 from said segments. Fig. 8 is a vertical section on line 8—8 of Fig. 1.

Throughout the several views similar reference numerals indicate similar parts.

In the drawings, 1 represents the cement 65 lining designed to properly cover the bottom of the turn table pit and the vertical walls thereof. Upon the bottom of the pit is located the inner fixed track 2, which track is provided upon its upper surface with a 70 groove or trough adapted to receive and hold in proper position a series of anti-friction balls 3, which balls are adapted to normally carry the weight of the rotatable portion of the turn table. For the purpose of providing 75 means for causing the weight of the table to rest upon certain only of the balls 3 the bottom of the run-way or groove of the track 2 is formed with elevations 4, and depressions 5, which elevations and depressions 80 alternate in such a manner that those balls upon the elevations carry the weight of the turn table, the balls in the depressions being relieved from the weight and rolled down the incline; said balls in the depressions, however, being forced up the next incline by the balls behind the lower ones as 85 the table is revolved.

Directly above the track 2 is located the turn table support proper 6, which is circular 90 in form and of a diameter corresponding substantially with the diameter of the circular track 2 so that said turn table support will ride upon the balls 3 as illustrated in Fig. 8. For the purpose of holding the 95 support 6 in proper relation with reference to the track 2 the fixed center post 7 is provided, which center post is secured to the hub 8, which hub is held by means of the spokes 9. The center post is extended into 100 the hub 10, which hub is formed at the junction of the webs 11. The turn table support 6 is composed of said hub 10, the inner cylindrical member 12 and the outer ring 13 all joined together by means of the said 105 webs 11 and the webs 14. The top or upper edge of the cylindrical portion 12 is provided with the shoulder 15, which shoulder

is designed to support a center plate 16. The cylindrical member 12 is provided with a series of openings 17 near its upper edge, the number of such openings corresponding 5 with the number of the trusses designed to be connected thereto. A corresponding number of openings 18 are provided in the outer ring 13 of the turn table support 6. The inner ends of the trusses are provided 10 with the upper and lower screw threaded heads 19 and 20, which heads extend through the openings 17 and 18 respectively and upon which the nuts 21 and 22 are located. The trusses consist of the upper angle bars 15 23 and the lower angle bars 24, tied together by means of the web plates 25.

To the outer ends of the trusses are connected a series of segments 26, which segments when properly connected together 20 constitute a ring rotatable with the turn table proper. Below this ring formed of segmental sections 26 is located the fixed track 27, which is formed of a diameter corresponding substantially with the diameter 25 of the connected segments 26 or the ring made up of such segments. The track 27 is held in proper concentric position by the spokes 28, said spokes being detachably connected at their ends to the track 2 and to the 30 ring 27 as illustrated in Fig. 4. To the segmental sections 26 and preferably at their joints are attached the connecting blocks 29, which blocks are provided with the casters 30. The casters are normally held slightly 35 elevated and out of contact with the outer track 27, but in the event of a heavy weight being placed upon the turn table near the periphery thereof the casters adjacent said weight will be lowered and caused to bear 40 upon the outer track 27, the entire turn table proper being very slightly tilted, thus relieving the structure of undue strain.

It will be understood that in order to provide a turn table easily operated, the weight 45 should be carried relatively near the center or axis and hence the trusses should be so adjusted that the casters 30 will normally be held out of contact with the track 27. The weight will thus normally be carried 50 by the balls 3. This is also the condition when an automobile or other object of weight is upon the turn table properly balanced. When, however, the weight is not balanced but is to one side of the center the 55 casters 30 will assist in carrying the load.

The outer ring 13 of the turn table support 6 is of considerably greater diameter than the inner cylindrical portion 12. Accordingly the lower angle bars 24 of the 60 trusses are shorter than the upper angle bars 23, thus bringing the point of attachment of each lower head 20 at a point intermediate the ends of the upper angle bar 23 of the truss. This feature is well illustrated 65 in Fig. 8. It will thus be seen that when

the weight on the turn table is located between the center of said table and a point in vertical alinement with the attachment of the head 20 the strain will be directly downward upon that part of the truss intermediate the vertical line through the head 20 and the inner end of the upper angle bars 23. When, however, the object is located beyond a point in vertical alinement with the attachment of the head 20 the said 70 weight will produce certain strains and thrusts in the trusses which the construction herein set forth is especially well adapted to endure. The lower bars 24 being relatively short are well adapted to endure the 75 longitudinal thrust which is imparted to them while the web plates 25 distribute the strain as between the bars 23 and 24, portions of said web being under tractive and other portions under torsional strain. It 80 should also be noted that the distance between the points of attachment of the heads 19 and 20 is greater than the vertical distance between the head 20 and the top of the truss. This form of truss and attachment is therefore capable of sustaining a 85 greater load with less strain and with a more direct thrust upon that portion of the support 6 immediately above the balls 3 than if the heads 19 and 20 were arranged 90 vertically one above the other. In addition to this fact the construction herein described enables the use of a track 2 of sufficiently 95 large diameter to be practical while at the same time locating the nuts 21 on the heads 19 sufficiently close to the center of the device so that the center plate 16 need not be of great diameter or weight, said center plate being very readily removed when it is 100 desired to have access to the nuts 21 for the purpose of adjusting the trusses to maintain 105 the parts of the device in proper relative position.

It will be understood that in turn tables of the class described it is desirable that the 110 entire structure require but a shallow pit and from an inspection of the drawings it will be noted that the construction shown enables the use of the minimum depth of pit for a turn table adapted to be of practical 115 service in supporting heavy automobiles or other objects.

As it is necessary that the sector shaped plates 31 should be held against accidental displacement with reference to the center 120 plate 16 and the structure proper, and in order to provide against such displacement the bottom or under sides of each of the plates 31 are provided with tangs 32, which tangs extend under the upper truss bars 23. 125 For the purpose of holding the plates down and upon the segmental bars 26 the screws 33 are provided.

In order to provide for a proper drainage of the pit the bottom of the pit is provided 130

with a series of trenches 34, which trenches lead to the basin 35 from which basin leads the drain pipe 36.

In order to easily detach the spokes 28 the 5 sockets 37 should be open so that the inner ends can be lifted up and the bars 28 pulled from the sockets 38 formed in the outer track 27.

For the purpose of preventing the cement 10 from breaking or crumbling away at the top of the pit a metal band or inner hoop 39 preferably of angle iron should be provided.

I claim:

1. A turn table of the class described comprising an inner track, a series of balls located upon said inner track, a turn table support carried by the balls, said turn table support consisting of an inner cylindrical member and an outer ring member of greater 20 diameter than the cylindrical member, trusses adapted to be connected at their inner ends to said turn table support, the inner upper ends of said trusses being connected to said inner cylindrical member and the inner lower ends of said trusses connected to said outer ring members, and a series of plates connected to the trusses and forming a platform.

2. A turn table of the class described comprising inner and outer fixed concentric tracks, a turn table support rotatably mounted upon the inner track, radial trusses comprising spaced upper and lower bars, the upper bars connected to the turn table 30 support and the lower bars connected thereto at a point farther removed from the center of said support than the point at which the upper bars are connected, a ring secured to the outer ends of the trusses and a series of 35 plates connected to the trusses and adapted to form a platform.

3. A turn table comprising inner and outer fixed concentric tracks, a support rotatably mounted upon the inner track, radial 40 trusses adjustably connected to said support, said trusses comprising spaced upper and lower bars, said upper bars being substantially horizontal and of greater length than said lower bars, segmental sections secured 45 to the outer ends of the trusses adapted to form a ring, said ring located above the outer concentric track, casters connected to said outer ring, a center plate located above the support and a series of plates detachably secured to the trusses.

4. In a turn table of the class described, the combination of an inner track provided with alternating elevations and depressions, a series of balls located upon said inner 50 track, a turn table support carried by the balls, radial trusses comprising spaced upper and lower bars, the upper bars connected to the turn table support and lower bars connected thereto at a point farther removed from the center of said support than the point at

which the upper bars are connected, a ring secured to the outer end of the trusses, an outer track located beneath said ring and a series of plates connected to the trusses and forming a platform.

70

5. In a turn table of the class described, the combination of an inner track or way provided with alternating elevations and depressions, a series of balls located upon said inner track or way, a turn table support 75 carried by the balls, said turn table support consisting of an inner cylindrical member and an outer ring member of greater diameter than the cylindrical member, trusses connected at their inner ends to said turn table support, a ring secured to the outer ends of said trusses, an outer track located below said ring and a series of plates connected to the trusses and forming a platform.

6. A turn table comprising a rotatable 85 support provided with an upper relatively small circular member and a lower, concentric, relatively large circular member connected thereto, radially disposed trusses provided with relatively long upper chords 90 and relatively short lower chords, the inner ends of said upper chords connected to the upper circular member of said support, and the lower chords connected at their inner ends to the lower circular member of said 95 support, and a platform supported by said trusses.

7. A turn table comprising a rotatable support provided with an upper relatively small circular member and a lower, concentric, relatively large circular member connected thereto, radially disposed trusses provided with relatively long upper chords 100 and relatively short lower chords, the inner ends of said upper chords adjustably connected to the upper circular member of said support, and the lower chords connected at their inner ends to the lower circular member of said 105 support, and a platform supported by said trusses.

110

8. A turn table comprising a rotatable support provided with an upper relatively small circular member and a lower, concentric, relatively large circular member connected thereto, trusses provided with 115 relatively long upper chords and relatively short lower chords, the inner ends of said upper chords connected to the upper circular member of said support, and the lower chords connected at their inner ends to the lower circular member of said support, a platform supported by said trusses, said support mounted upon an inner bearing of relatively small diameter arranged concentrically with said support and adapted to 120 normally carry said turn table in a horizontal position and permit its rotation, and an outer, auxiliary normally inactive bearing arranged concentrically with the first mentioned bearing and adapted to assist 125 130

said first mentioned bearing in carrying the weight of said turn table when over-loaded or tilted.

9. A turn table comprising a rotatable support provided with an upper relatively small circular member and a lower, concentric, relatively large circular member connected thereto, trusses provided with relatively long upper chords and relatively short lower chords, the inner ends of said upper chords adjustably connected to the upper circular member of said support, and the lower chords connected at their inner ends to the lower circular member of said support, a platform supported by said trusses, said support mounted upon an inner bearing of relatively small diameter arranged concentrically with said support and adapted to normally carry said turn table in a horizontal position and permit its rotation, and an outer, auxiliary, normally inactive bearing arranged concentrically with the first mentioned bearing and adapted to assist said first mentioned bearing in carrying the weight of said turn table when over-loaded or tilted.

10. A turn table comprising a platform

mounted upon a supporting member and trusses, said supporting member rotatable and said trusses comprising relatively long 30 horizontal upper chords and relatively short, inclined lower chords connected together and to said supporting member.

11. In a turn table of the class described a platform supported by trusses connected 35 to a rotatable support, each of said trusses consisting of upper angle bars arranged horizontally and lower angle bars arranged in inclined position, said upper angle bars and lower angle bars tied together by means 40 of a web plate, upper and lower heads connected to the inner ends of said upper and lower angle bars, and said lower head arranged at a point longitudinally intermediate said upper head and the outer end of 45 said truss.

In testimony that I claim the above, I have hereunto subscribed my name in the presence of two witnesses.

ALBERTUS O. SLENTZ.
